HIGH SHUNTING SENSITIVITY TRACK
CIRCUITS

Crawford E. Staples, Edgewood, Pa., assignor to Westinghouse Air Brake Company, Wilmerding, Pa., a corporation of Pennsylvania

Filed Oct. 28, 1959, Ser. No. 849,372

8 Claims. (Cl. 246—34)

My invention relates to railway track circuit apparatus and more particularly to railway track circuits providing high shunting sensitivity.

Reliable operation of a track circuit of an insulated railway track section requires that a current source not only satisfactorily energize a track relay when the section is unoccupied but also requires that such current be effectively shunted away from the associated track relay when the section is occupied. It is known that a shunt effected through the wheels and axles of a train or car varies in its resistance due to the presence, at times, of a thin coating or film of relatively high resistance on the rail and/or wheel surfaces.

The problem of providing a satisfactory shunt is particularly complicated in automatic classification yards for various reasons. In such yards oily films are frequently encountered due to, for example, the drippings from freshly oiled wheel bearings, brine drippings from standing cars, etc. An oily film has a tendency to spread, to collect dirt, and to transfer from wheel to rail or vice versa depending on the temperature. This film resistance may be of such nature as to form a high resistance path to the low voltage usually employed in the track circuit and such low voltage will normally not break down or puncture the film.

The shunting problems are made more difficult in track circuits used for classification yards since the track sections employed are normally so short that only one or two axles (and the included wheels) are in a track section during a given occupancy time. Obviously the more axles present in a track section the higher the probability that at least one axle would provide a satisfactory shunt. Further the track circuits must be sensitive and fast in operation since a series of cars may be following one another in rather close succession and the command signals for each car must be initiated and transferred to the control center expeditiously and accurately.

The problem of providing a reliable shunting operation is further complicated in classification yards since it has been found that cars subjected to sharp curves or retardation have a tendency to bounce and roll particularly at switches, points, frogs, and rail joints, thus resulting in momentary losses of shunt. In order to overcome the momentary losses of shunt a short time delay in the reset of the track circuit must be provided. Thus, the track circuit desirably includes a track relay having a quick shunting but slow pickup characteristics.

It has been found that the characteristics of conventional track circuits are such that the current flowing in the track relay varies considerably from a minimum operating value when the ballast resistance is low to a maximum value when the ballast resistance is high. This makes it difficult to maintain the timing of the track relay at a relatively constant value, since the track relay when highly energized picks up quickly and when shunted releases rather slowly. It is known that greatly increased shunting sensitivity of a track circuit can be obtained by increasing the voltage impressed across rails since a high voltage tends to break down the nonconductive film to permit track circuit current to flow through the wheel and axle units. However, if a high voltage is steadily applied between the rails the track circuit power input tends to become excessive, especially under wet weather

2

conditions when the ballast resistance is relatively low. Further, when dry weather conditions exist, a high voltage impressed across rails tends to over-energize the track relay as well as to create other undesirable conditions, such as affecting the operation of adjacent track circuits.

Accordingly it is a principal object of my invention to provide a track circuit having a high shunting sensitivity.

It is another object of my invention to provide a track circuit including a relay having a fast release time and a slow pickup time.

It is another object of my invention to provide a track circuit capable of shunting through high resistance film while utilizing a minimum of power.

In the attainment of the foregoing objects I provide a track circuit including means for connecting an alternating current across one end of the track section. The track circuit further includes a saturating or saturable and a nonsaturating or nonsaturable transformer having their primary windings connected in series with one another across the track rails at the other end of the track section. The saturating transformer is adjusted to saturate at the minimum ballast resistance expected to exist across the track rails for providing a substantially constant voltage thereacross over a wide range of track voltages. Thus a change in the voltage across the track rails provides a greater percentage change in the voltage appearing across said nonsaturating transformer. The output of the saturating transformer is rectified and is connected through a first P-N-P transistor, which transistor operates as a switch means, to energize a track relay. The output of the nonsaturating transformer is rectified and connected to bias a second P-N-P transistor to be normally conducting. The unsaturating transformer also provides a voltage to a relatively large capacitor, and a relatively high resistance connected across said capacitor. The more positive terminal of the capacitor is connected to the base of the second P-N-P transistor. The biasing network of the first transistor is connected to include the emitter to collector path of the second transistor and when the second transistor is conducting the bias voltage applied to the first transistor is such to cause the first transistor to be conducting heavily. When the current flow through the second transistor is decreased the biasing voltage applied to the first transistor is such as to cause the current through the first transistor to also decrease and thereby deenergize the track relay. When a high resistance shunt occurs across the track rails, the saturated transformer will be negligibly affected, however, the output of the nonsaturating transformer will drop causing the capacitor to discharge relatively slowly through the high resistance. Since the base voltage of the second transistor will be higher than its emitter voltage, the emitter to collector path of the second transistor will become a high impedance causing the current flow through the first transistor to decrease and the track relay to be deenergized for a period of time dependent on the discharge time of the capacitor.

It should be understood at the outset that although P-N-P type transistors are employed in the embodiment described, N-P-N type transistors could likewise be used by proper reversal of the bias voltage, and by providing suitable connections from the capacitor to the proper electrodes to cut off the second transistor.

Other objects and advantages of my invention will become apparent when the following description and the accompanying drawing in which the sole figure is a schematic diagram of the track circuit according to my invention.

Referring to the figure the reference characters 11a and 11b designate rails of a railway track section 10 insulated by rail joints 13a and 13b from adjacent track sections. Alternating current to the track section is sup-

plied from an alternating current source 9 of any suitable type, say a 115 volt 60-cycle source, through a transformer 15 having primary and secondary windings 17 and 19. One terminal of the secondary winding 19 is connected through lead 22 to track rail 11a at one end, the left-hand end as oriented in the figure, of track section 10 and the other terminal of secondary winding 19 is connected through lead 24 and an adjustable resistor 21 to track rail 11b also at the left-hand end of track section 10.

The usual ballast resistance existing across track rails 11a and 11b is indicated by the dotted resistors 14 connecting the two rails. As is known, the ballast resistance may vary from a minimum to a maximum depending upon moisture, temperature, etc. A shunt resistance on the track section 10 is indicated by the wheel and axle unit 16.

Current energy is taken from the track rails 11a and 11b by a pair of transformers 25 and 31; transformer 25 being of a nonsaturable or nonsaturating type and transformer 31 being of a saturable or saturating type. Instead of a pair of transformers, a single transformer having a pair of output windings, one winding providing a relatively constant output and the other a variable output as, for example, two output windings wound on an iron core with one winding having no air gap and the other winding having an air gap, might be used. One terminal of the primary winding 23 of nonsaturable transformer 25 is connected through lead 16 to one terminal of the primary winding 29 of saturable transformer 31. The other or second terminal of primary winding 23 is connected through lead 18 to track rail 11b at a point on the right-hand end of track section 10; and the other or second terminal of primary winding 29 is connected through lead 20 to rail 11a at a point also at the right-hand end of track section 10. The primary windings 23 and 29 are thus connected in series across the track rails 11a and 11b for purposes to be described hereinbelow. The secondary winding 33 of transformer 31 is connected across the alternating current terminals 32 and 34 of a full-wave diode rectifier 35 of the well known type. The secondary winding 27 of transformer 25 is connected across the alternating current terminals 40 and 42 of a full-wave diode rectifier 37 which is similar to rectifier 35.

The positive direct current terminal 36 of rectifier 35 is connected in series through a diode 39 to provide a positive voltage to the emitter 41 of a P-N-P type transistor 43. Diode 39 provides a substantially constant voltage drop thereacross irrespective of the current flowing through transistor 43. A filtering capacitor 49 is connected in parallel to diode 39 to dampen any voltage variations across the diode. The junction of emitter 41, diode 39 and capacitor 49 is connected through resistor 51 to the negative terminal 38 of rectifier 35. Transistor 43 includes, in addition to emitter 41, a base 45 and a collector 47. The collector 47 is connected through an adjustable resistor 53 to the operating coil of a track relay 55 and thence to the negative potential terminal 38 of rectifier 35. Collector 47 thus provides the operating current to relay 55 to actuate relay contacts *a*. Resistor 53 permits an initial fine adjustment of the voltage applied to relay 55.

As is known, varistor 57 changes its resistance dependent on the voltage existing thereacross. When transistor 43 is cut off an inductive kick is developed in the operating coil of relay 55. This inductive kick is dissipated in the circuit including varistor 57, resistor 53 and coil or relay 55; thus protecting transistor 43 from any high voltage surges.

The positive terminal 36 of rectifier 35 is also connected serially through a thermistor 63, a resistor 65 and a resistor 61 to the base of transistor 43 to provide a voltage to base 45 which voltage is less positive than the voltage applied to emitter 41. Transistor 43 is thus biased to be normally conducting, and in fact in one embodiment, the circuit components are chosen such that transistor 43 is conducting relatively heavy current. As is known,

thermistor 63 has a negative temperature coefficient to compensate for temperature variations, and thus tends to provide a relatively more constant emitter 41 to base 45 bias. A capacitor 59 is connected in parallel to thermistor 63 and resistor 65 for purposes described hereinbelow.

As noted, the alternating current terminals 40 and 42 of rectifier 37 are connected across non-saturable transformer 25. A filter circuit comprising inductor 66 connected in series with direct current terminal 44 and a capacitor 67 connected in series with inductor 66 and across direct current terminals 44 and 46 provides a smooth direct current output to bias transistor 81. A parallel network comprising a resistor 69, a capacitor 71 and a variable resistor 73 are connected in that order across terminals 44 and 46 and in parallel with one another. Resistor 69 serves as a load resistor; the function of capacitor 71 and resistor 73 will be described hereinbelow.

The emitter 83 of transistor 81 is connected through a resistor 91 and a diode 75 to the positive terminal 44. The base 79 of transistor 81 is connected through resistor 77 and diode 75 to terminal 44. Base 79 is also connected directly to one side of capacitor 71. Resistor 77 provides a voltage drop between emitter 83 and base 79 to forward bias transistor 81. Diode 75 is poled to become nonconductive and essentially an open circuit when the potential across capacitor 71 is more positive than the potential appearing across terminals 44 and 46 of rectifier 37. A filtering capacitor 87 is connected in parallel with resistor 77 and tends to maintain a constant voltage across resistor 77. A resistor 89 is connected in series between the positive terminals of capacitor 71 and resistor 73.

Emitter 83 of transistor 81 is also connected through resistor 91, and a diode 93 to the junction of resistor 65, capacitor 59 and resistor 61. The other terminal of resistor 61 is connected to the base 45 of transistor 43. Diode 93 is poled to prevent any positive voltages coupled to emitter 83 from rectifier 37 and/or capacitor 71 from appearing on the base 45 of transistor 43. Collector 85 of transistor 81 is connected through a resistor 94 and lead 96 to the negative terminal 38 of rectifier 35 which rectifier, as noted above also, provides the biasing voltages for transistor 43.

A lightning arrester 95 is desirably connected across leads 18 and 20 to protect the track circuitry from high voltage surges.

In operation, the voltage appearing across track rails 11a and 11b is adjusted by means of resistor 21 to provide a sufficient voltage across the series connected primary windings 23 and 29 of transformers 25 and 31, respectively, to saturate saturable transformer 31. As is known, when transformer 31 is saturated it will provide a practically constant output voltage under all ballast resistance and shunt resistance conditions above a minimum operating level. The voltage output of nonsaturable transformer 25 is a function of the difference between the voltage existing across the track rails and the voltage existing across the saturable transformer 31. Consequently, a variation in the voltage existing across said track rails causes a proportionally larger output voltage variation across transformer 25. This is the case due to the fact that when a high resistance shunt is applied across the track rails 11a and 11b, and although there be only a slight drop in the rail voltage, practically all the change of voltage appears across the nonsaturable transformer 25 since the saturable transformer 31 tends to maintain a constant voltage. Consequently, the voltage across terminals 40 and 42 of rectifier 37 drops rather sharply.

It should be appreciated that in the present circuit both transistors 43 and 81 are employed essentially as switching devices. Transistor 43 controls current flow through relay 55 while transistor 81 controls the operation of transistor 43 as will be explained hereinbelow. Under normal conditions with no shunt resistance present

across the track rails 11a and 11b, transistor 43 is forward biased to be conducting a rather heavy current and track relay 55 obtains normal operating or energizing current, and the relay contacts a are picked up. As noted, diode 39 and resistor 51 are connected across terminals 36 and 38 of rectifier 35, and emitter 41 is connected to the junction of diode 39 and resistor 51. The voltage drop across diode 39 will be constant and relatively low; thus the voltage impressed on emitter 41 will be approximately one-half volt lower than the voltage present at terminal 36. Thermistor 63, resistor 65, diode 93, resistor 91, the emitter 83 to collector path 85 of transistor 81, and resistor 94 are connected across terminals 36 and 38 of rectifier 35. When transistor 81 is conducting heavily the circuit just traced provides a voltage divider network which includes a relatively low emitter 83 to collector 85 impedance for providing a positive voltage to base 45. The voltage on base 45 will be a portion of the voltage developed across terminals 36 and 38 and will be somewhat less positive than the voltage on emitter 41. Since transistor 43 is of the P-N-P type, when the emitter 41 is more positive than base 45, transistor 43 will conduct rather heavily.

However, as is well known, when transistor 81 is either barely conducting or cut off the emitter 83 to collector 85 impedance will be relatively large. The voltage divider network for base 45, previously traced above, will now include the high impedance of the emitter to collector path of transistor 81 and the voltage applied to base 45 will tend to be closer to the voltage on terminal 36. The voltage on emitter 41 will be approximately one-half volt lower than the voltage appearing on the terminal 36 due to the drop across diode 39. In this condition transistor 43 will be reversed biased, that is, base 45 will be more positive than emitter 41 and current flow through transistor will be decreased or cut off.

The biasing voltages for transistor 81 which transistor in turn controls the operation of transistor 43 are as follows. Under normal conditions with the track circuit not shunted, a positive voltage is applied from the positive terminal 44 of rectifier 37 through diode 75 and resistor 91 to emitter 83, and through the diode 75 and resistor 77 to base 79. The upper terminal, as oriented in the drawing, of resistor 77 is connected to the junction of diode 75 and resistor 91, while its lower terminal is connected to base 79. Due to the voltage drop across resistor 77 the voltage applied to base 79 is less positive than the voltage applied to emitter 83. Transistor 81 is thus forward biased and is normally conducting.

As noted above, capacitor 71 is charged to a voltage somewhat lower than the voltage across terminals 44 and 46 through the voltage dropping resistor 77. When the track rails are shunted, the voltage appearing across transformer 25 and across rectifier terminals 44, 46 will drop causing the voltage on emitter 83 to also drop.

However, the voltage across capacitor 71 changes relatively slowly since capacitor 71 which is relatively large must discharge through resistor 89 and relatively high resistance resistor 73. Diode 75 is poled to assure the discharge path of capacitor 71 is through resistor 73. Typical values for capacitor 71 and resistor 73 as used in one embodiment of the invention are 500 mfd. and 100K ohms, respectively. Thus, for a definite period of time, determined by the discharge time of capacitor 71, the voltage appearing on base 79 will be more positive than the voltage appearing on emitter 83. In other words, the voltage on emitter 83 drops to a low value quickly, while the voltage on the base 79 will drop relatively slowly. Consequently, the transistor 81 will be reversed biased during the foregoing period of time and current flow therethrough will be decreased causing its emitter 83 to collector 85 path to become a high impedance. As discussed above, when transistor 81 has a decreased current flow therethrough transistor 43 will also have a decreased current flow therethrough or may be cut off. In

any case, the current flow through the operating coil of track relay 55 will be decreased sufficiently to deenergize the relay. A time delay for track relay 55 is provided by capacitor 59. With transistor 81 barely conducting or cut off the lower terminal, as oriented in the drawing, of capacitor 59 is approximately at the positive potential of terminal 36 of rectifier 35. That is, at this instant little or no voltage exists across capacitor 59. As noted above, when transistor 81 begins to conduct more heavily, 10 the impedance of the emitter 83 to collector 85 path decreases. The voltage at the junction point of resistor 65, capacitor 59, diode 93 and resistor 61 will now tend to decrease in potential due to the voltage dividing action of the circuit traced from terminal 36, thermistor 63, resistor 65, diode 93, resistor 91, emitter 83 to collector 85, and resistor 94 to terminal 38. However, before the foregoing junction point can decrease in potential, capacitor 59 which as noted above had little or no voltage appearing thereacross must now charge to the difference in 20 voltage existing between terminal 38 and the junction point. Capacitor 59 therefore charges through the circuit traced from its lower plate, diode 93, resistor 91, transistor 81 and resistor 94 to terminal 38. Thus the voltage differential or bias between emitter 41 and base 25 45 will depend on the charging time of capacitor 59 through the foregoing circuit, and the conduction of transistor 43 and the flow of current through relay 55 will be delayed.

The time delay provided by capacitor 59 is in the order 30 of 0.1 second. The inherent time delay in the coil of relay 55 is about 0.3 second so that the total time delay measured from the time shunt 16 is removed from track section 10 until relay 55 contacts a pickup is approximately 0.4 second. Since the voltage appearing 35 across the saturable transformer 29 is substantially constant for all ballast conditions, the pickup time of the track relay 55 remains practically constant for all ballast conditions.

In order to hold the track relay 55 down indefinitely, 40 the shunt resistance must be low enough to reduce the voltage across the saturable transformer 29 sufficiently to reduce the current flow through track relay 55 to the relay release value. The shunt resistance which will hold track relay 55 permanently in the released or deenergized position is, of course, lower than the minimum operating ballast resistance. However, a momentary shunt of higher resistance than the ballast resistance will deenergize the track relay for a period of time as described above.

In practice it has been found that a moving wheel and 50 axle unit entering a track section initially provides a high resistance shunt. Therefore, my circuit is particularly useful as a high sensitivity circuit to quickly detect the presence of a train in the track section. Also, the film on the rail is normally found in spots so that my circuit adds 55 to the inherent delay time of the track relay to maintain the relay deenergized while the moving wheel and axle unit passes over the film spot.

Although I have herein shown and described only one 60 form of apparatus embodying my invention, it will be understood that various changes and modifications may be made therein within the scope of the appended claims without departing from the spirit and scope of my invention.

Having thus described my invention, what I claim is:

65 1. A track circuit for a section of railway track having ballast resistance existing across the track rails comprising, in combination, means providing alternating current energy to said track rails, a saturable transformer and a nonsaturable transformer each having a primary winding 70 and a secondary winding, the primary winding of said saturable transformer and the primary winding of said nonsaturable transformer being connected in series with each other across said track rails, said saturable transformer developing a substantially constant voltage thereacross over a range of voltages appearing across said

track rails, said nonsaturable transformer developing a voltage thereacross which is the difference between the voltage existing across said track rails and the voltage across said saturable transformer whereby a voltage change across said track rails develops a proportionally larger change across said nonsaturable transformer, first and second bridge rectifiers each having a pair of alternating current terminals and a pair of direct current terminals, the alternating current terminals of said first and second rectifiers being connected across said secondary windings of said nonsaturable and saturable transformers respectively, a track relay having an operating coil, first and second P-N-P type transistors each having base, emitter and collector electrodes, means connecting the output current of said second transistor to energize said track relay coil, first and second biasing means connecting the direct current terminals of said first and second rectifiers to said first and second transistors respectively for biasing said transistors to a first state of normal current flow therethrough, said first biasing means including a capacitor having its two terminals connected to said first rectifier to be charged to a portion of the direct current voltage existing across said first rectifier, a resistive element connected across said capacitor, a diode connected in series intermediate said capacitor and said first rectifier with a polarity to cause said capacitor to discharge through said resistive element, the terminal of capacitor which is positively charged being connected to the base of said first transistor, said first transistor being biased to a second state of reduced current flow therethrough by the potential on said capacitor when the voltage across said first rectifier drops, said capacitor maintaining said first transistor in said second state for a period dependent on the time required by said capacitor to discharge through said resistive element to a potential less than that appearing across said rectifier, said second biasing means including a voltage divider network having its ends connected across the direct current terminals of said second rectifier, said divider network comprising impedance elements connected in series with the emitter-to-base path of said second transistor, said base of said second transistor being connected to a point on said network between the positive terminal of said rectifier and the emitter-to-base path of said first transistor, said first transistor when in said first conducting state forming an effectively low impedance element in said network for causing the voltage applied to the base of said second transistor to be higher than the voltage on the emitter of said second transistor to bias said second transistor to said first conducting state, and said first transistor when in said second state forming an effectively high impedance element in said network for causing the voltage applied to the base of said second transistor to bias said second transistor to a second state of reduced current flow and thereby decrease current flow to said track relay coil.

2. A track circuit for a section of railway track having resistance existing across the track rails comprising, in combination, means providing alternating current energy to said rails, first and second transformer means for coupling energy from said rails, first and second rectifying means being connected to rectify the output of said first and second transformer means respectively, a track relay having an operating coil, first and second transistors each having base, emitter and collector electrodes, means connecting the output current of said second transistor to energize said track relay coil, first and second biasing means connecting said first and second rectifying means to said first and second transistors respectively for biasing said transistors to a first state of current flow therethrough, said first biasing means including a capacitor having its two terminals connected to said rectifying means so that said capacitor is charged to a portion of the voltage existing across said first rectifying means, a resistive element connected across said capacitor, current blocking means connected intermediate said capacitor and said first rectifier for connecting the output of said first rectifier to the base of said first transistor, said first rectifier having an operating coil, first and second transistors each having base, emitter and collector electrodes, means connecting the output current of said second transistor to energize said track relay coil, first and second biasing means connecting said first and second rectifying means to said first and second transistors respectively for biasing said transistors to a first state of current flow therethrough, said first biasing means including a capacitor having its two terminals connected to said rectifying means so that said capacitor is charged to a portion of the voltage existing across said first rectifying means, a resistive element connected across said capacitor, current blocking means connected intermediate said capacitor and said first rectifier for causing the discharge path for said capacitor to be through said resistive element, one terminal of said capacitor being connected to the base of said first transistor, said first transistor being biased to a second state of reduced current flow therethrough by the potential on said capacitor when the voltage appearing across said first rectifier drops, said capacitor maintaining said first transistor in said second state for a period dependent on the discharge time of said capacitor through said resistive element, said second biasing means including a voltage divider network having its ends connected across said second rectifier, said divider network comprising impedance elements connected in series with the emitter-to-base path of said second transistor, said base of said second transistor being connected to a point on said network between a terminal of said second rectifier and the

means for causing the discharge path for said capacitor to be through said resistive element, one terminal of said capacitor being connected to the base of said first transistor, said first transistor being biased to a second state of reduced current flow therethrough by the potential on said capacitor when the voltage across said first rectifying means drops, said capacitor maintaining said first transistor in said second state for a period dependent on the discharge time of said capacitor through said resistive element, said second biasing means including a voltage divider network having its ends connected across said second rectifying means, said divider network comprising impedance elements connected in series with the emitter-to-base path of said first transistor, the base of said second transistor being connected to a point intermediate the ends of said network, said first transistor when in said first conducting state forming an effectively low impedance element of said network for causing the voltage applied to the base of said second transistor to bias said second transistor to said first conducting state, and said first transistor when in said second state forming an effectively high impedance element in said network for causing the voltage applied to the base of said second transistor to bias said second transistor to a second conducting state of reduced current flow and thereby decrease current flow to said track relay coil.

3. A track circuit for a section of railway track having resistance existing across the track rails comprising, in combination, means providing alternating current energy to said rails, a saturable transformer and a nonsaturable transformer each having a primary winding and a secondary winding, the primary winding of said saturable transformer and the primary winding of said nonsaturable transformer being connected in series with each other across said track rails, said saturable transformer developing a substantially constant voltage thereacross over a range of voltages appearing across said track rails, said nonsaturable transformer developing a voltage thereacross which is the difference between the voltage existing across said track rails and the voltage across said saturable transformer whereby a voltage change across said track rails develops a proportionally larger change across said nonsaturable transformer, first and second rectifiers being connected across said secondary windings of said nonsaturable and saturable transformers respectively for rectifying the outputs of said transformers, a track relay having an operating coil, first and second transistors each having base, emitter and collector electrodes, means connecting the output current of said second transistor to energize said track relay coil, first and second biasing means connecting the outputs of said first and second rectifiers to said first and second transistors respectively for biasing said transistors to a first state of current flow therethrough, said first biasing means including a capacitor having its terminals connected to said first rectifier so that said capacitor is charged to a portion of the voltage existing across said first rectifier, a resistive element connected across said capacitor, current blocking means connected intermediate said capacitor and said first rectifier for causing the discharge path for said capacitor to be through said resistive element, one terminal of said capacitor being connected to the base of said first transistor, said first transistor being biased to a second state of reduced current flow therethrough by the potential on said capacitor when the voltage appearing across said first rectifier drops, said capacitor maintaining said first transistor in said second state for a period dependent on the discharge time of said capacitor through said resistive element, said second biasing means including a voltage divider network having its ends connected across said second rectifier, said divider network comprising impedance elements connected in series with the emitter-to-base path of said second transistor, said base of said second transistor being connected to a point on said network between a terminal of said second rectifier and the

emitter-to-base path of said first transistor, said first transistor when in said first conducting state forming an effectively low impedance element in said network for causing the voltage applied to said base of said second transistor to bias said second transistor to said first conducting state, and said first transistor when in said second state forming an effectively high impedance element in said network for causing the voltage applied to the base of said second transistor to bias said second transistor to a second conducting state of reduced current flow and thereby decrease current flow to said track relay coil.

4. A track circuit for a section of railway track having resistance existing across the track rails, comprising, in combination, means connecting electrical energy to said rails for providing a voltage across said track rails which is a function of the resistance existing across said track rails, first and second means for coupling electrical energy from said track rails to the remainder of said track circuit, said second coupling means providing a substantially constant voltage over a range of voltages appearing across said track rails, said first coupling means providing a voltage which is the difference between the voltage appearing across said track rails and the voltage provided by said second coupling means whereby a voltage change across said track rails due to a change in the resistance across said track rails develops a proportionally larger voltage change across said first coupling means, a track relay, switch means for at times connecting said track relay to receive energy from said second coupling means, means for controlling the operation of said switch means, means for connecting said controlling means to said first coupling means to receive energy therefrom, said controlling means being deenergized when the resistance across said track rails decreases, and said controlling means when deenergized opening said switch means for a limited period of time to decrease current flow through said relay during said limited period of time.

5. A track circuit for a section of railway track having resistance existing across the track rails comprising, means connecting electrical energy to said track rails for providing a voltage across said track rails which is a function of the resistance existing across said track rails, a first and second impedance means connected in series with each other across said track rails for developing voltages thereacross, said first impedance means developing a substantially constant voltage thereacross over a range of voltages appearing across said track rails, said second impedance means developing a voltage thereacross which is the difference between the voltage existing across said first impedance whereby a voltage change across said track rails develops a proportionally larger change across said second impedance, a track relay having an operating coil, switch means for at times connecting said track relay coil to receive energy from said first impedance means, means for controlling the operation of said switch means, said controlling means including a capacitor and a resistive element, said capacitor being connected to said second impedance means to be charged to a voltage which is a portion of the voltage appearing on said second impedance means, the voltage on said capacitor deenergizing said controlling means when the energy appearing on said second impedance means decreases due to a decrease in the resistance across said track rails, said controlling means being deenergized for a period dependent on the time required for said capacitor to discharge through said resistive element to a voltage less than that on said second impedance means, and said controlling means when deenergized opening said switch means to thereby interrupt current flow through said track relay coil for a limited period of time.

6. A track circuit for a section of railway track having resistance existing across the track rails comprising, means connecting electrical energy to said track rails for providing a voltage across said track rails which is a function of the resistance appearing across said track

rails, first and second impedance means connected in series with each other across said track rails for developing voltages thereacross, said first impedance means developing a substantially constant voltage thereacross over a range of voltages appearing across said track rails, said second impedance means developing a voltage thereacross which is the difference between the voltage existing across said track rails and the voltage across said first impedance whereby a voltage change across said track rails develops a proportionally larger change across said second impedance, a track relay having an operating coil, first and second transistors each having base, emitter and collector electrodes, means connecting the output current of said first transistor to said relay operating coil for energizing said relay, first biasing means connecting the voltage developed across said first impedance means to bias said first transistor to be conducting a preset current, said first biasing means including the emitter to collector path of said second transistor, second biasing means connecting the voltage developed across said second impedance means to bias said second transistor to be conducting a preset current, said second biasing means including a capacitor connected to said second impedance means to be charged to a portion of the voltage developed across said second impedance means, a resistive element connected across said capacitor, current blocking means connected for causing said capacitor discharge path to be through said resistive element, said second transistor being biased to conduct less than the preset current when the voltage across said second impedance drops to a value less than the voltage on said capacitor, said second transistor conducting less than the preset current for a time dependent on the discharge time of said capacitor through said resistive element, and said second transistor when conducting less than the preset current changing said first biasing means to cause said first transistor to also conduct less than the preset current and thereby deenergize said relay coil.

7. A track circuit for a section of railway track having resistance existing across the track rails comprising, in combination, means for coupling alternating current to said track rails for providing a voltage across said track rails which is a function of the resistance appearing across said track rails, a saturable transformer and a nonsaturable transformer each having input and output windings, the input windings of said transformer being connected in series with each other across said track rails, first and second rectifier means for rectifying the output of said output windings of said saturable and nonsaturable transformers respectively, first and second transistors each having base, emitter and collector electrodes, a track relay having an operating coil connected to receive energizing current from said first transistor, a first biasing circuit connecting the rectified output of said saturable transformer to bias said first transistor to be conducting a given normal current, said first biasing circuit including a voltage dividing network connected across said first rectifying means, said voltage dividing network including the emitter-to-base path of said second transistor, a second biasing circuit connecting the rectified output of said nonsaturable transformer to bias said second transistor to be conducting a given normal current, said second biasing circuit including a capacitor connected to said nonsaturable transformer rectifying means to be charged to a portion of the voltage developed across said nonsaturable transformer, a resistive element connected across said capacitor, current blocking means connected to cause the discharge path of said capacitor to be through said resistive element, said second transistor being biased to conduct a less than normal current flow therethrough by the voltage existing across said capacitor when the voltage across said nonsaturable transformer drops due to a change in the resistance existing across said track rails, said second transistor conducting less than normal current for a time dependent on the discharge time constant of said capacitor

through said resistive element, and said second transistor when conducting less than normal current effecting a series high impedance element in said voltage dividing network and changing the bias on said first transistor causing said first transistor to have less than normal current flow therethrough for deenergizing said relay.

8. A track circuit for a section of railway track having resistance existing across the track rails comprising, in combination, means for coupling alternating current to said track rails for providing a voltage across said track rails which is a function of the resistance appearing across said track rails, a saturable transformer and a non-saturable transformer each having input and output windings, the input windings of said transformer being connected in series with each other across said track rails, means for rectifying the output of said output windings, first and second transistors each having base, emitter and collector electrodes, a track relay having an operating coil connected to receive energizing current from said first transistor, a first biasing circuit connecting the rectified output of said saturable transformer to bias said first transistor to be normally conducting, said first biasing circuit including the emitter to base path of said second transistor, a second biasing circuit connecting the rectified output of said non-saturable transformer to bias said second transistor to be in nor-

20 mally conducting states, said second biasing circuit means including a capacitor connected to said non-saturable transformer rectifying means to be charged to a portion of the voltage developed across said non-saturable transformer, a resistive element connected across said capacitor, current blocking means connected to cause the discharge path for said capacitor to be through said resistive element, said second transistor being biased to a second state of decreased current flow therethrough by 10 the voltage across said capacitor when the voltage across said non-saturable transformer drops due to a change in the resistance appearing across said track rails, said second transistor remaining in said second state for a time dependent on the discharge time constant of said capacitor through said resistive element, said second transistor when in said second state opening said first biasing circuit for changing the bias on said first transistor causing said first transistor to a state of decreased current flow therethrough for deenergizing said relay.
